(57) CLAIM

The ornamental design for a sock, as shown and described.

DESCRIPTION

FIG. 1 is a front perspective view of a sock showing my new design in an in-use configuration;

FIG. 2 is a bottom rear perspective view thereof;

FIG. 3 is a side view thereof;

FIG. 4 is a second side view thereof;

FIG. 5 is a front view thereof;

FIG. 6 is a rear view thereof;

FIG. 7 is a top view thereof, and,

FIG. 8 is a bottom view thereof.

The broken lines showing the remainder of the sock are for the purpose of illustrating portions of the article that form no part of the claim.
